Primary Examiner — Clare E Heflin(74) *Attorney, Agent, or Firm* — Brown & Michaels, PC(57) **CLAIM**

The ornamental design for a housing for LED lighting fixture, as shown and described.

DESCRIPTION

FIG. 1 is a perspective view of the housing for LED lighting fixture of the present invention.

FIG. 2 is a side view of the housing for LED lighting fixture.

FIG. 3 is a side view of the housing for LED lighting fixture, showing the opposite side from FIG. 2.

FIG. 4 is a top view of the housing for LED lighting fixture.

FIG. 5 is a bottom view of the housing for LED lighting fixture.

FIG. 6 is a front view of the housing for LED lighting fixture.

FIG. 7 is a back view of the housing for LED lighting fixture; and,

FIG. 8 is another perspective view of the housing for LED lighting fixture.

The broken lines shown on the drawings depict portions of the housing for LED lighting fixture, that form no part of the claimed design.
